UNITED STATES PATENT OFFICE.

HUGO H. WERMINE, OF VILLA PARK, ILLINOIS, ASSIGNOR TO BELDEN MANUFACTURING COMPANY, OF CHICAGO, ILLINOIS, A CORPORATION OF ILLINOIS.

DESIGN FOR AN ELECTRIC PLUG CONNECTER.

Application filed February 26, 1927. Serial No. 20,912. Term of patent 14 years.

To all whom it may concern:

Be it known that I, HUGO H. WERMINE, a citizen of the United States, residing in Villa Park, Du Page County, and State of Illinois, have invented a new, original, and ornamental Design for Electric Plug Connecter, of which the following is a specification, reference being had to the accompanying drawing, forming a part thereof.

Figure 1 is a perspective view of a plug

connecter embodying my new design, and

Fig. 2 is a side elevation, and

Fig. 3 is also a side elevation showing the right hand side of the plug when in the position of Fig. 2.

I claim:

The ornamental design for an electric plug connecter substantially as shown.

HUGO H. WERMINE.
